DUPLICATING MEANS AND METHOD

Application filed November 23, 1931. Serial No. 576,736.

My invention relates to duplicating means and method with particular reference to means and method whereby more than the usual number of copies may be made on a duplicating machine from a single original such as a typewritten sheet.

My invention is applicable for use with that class of machines commonly known as hectographs or duplicating machines usually having a flat printing bed over which is stretched a long and comparatively thin gelatinized band or apron, the ends of the band being secured to or wound on spools adjacent the ends of the printing bed so that by rotating the spools, successive sections of the band may be exposed in operative position on the bed.

In this type of machine a platen carriage having a suitable platen roller thereon is adapted to travel over the printing bed for the purpose of impressing the original or the copy sheets on the gelatinized band which latter receives the imprint from the original sheet and transfers it to the copy sheets.

My invention is particularly adapted for use with duplicating machines of a type similar to that shown in my co-pending application, Serial No. 349,876, filed March 25, 1929, and my co-pending application Serial No. 529,629, filed April 13, 1931.

The invention may be used in connection with substantially any of the common types of duplicators in which the paper applying means and the bed are relatively movable and is particularly adapted for those having a movable carriage. The usual method of operating a duplicating machine similar to those mentioned is to provide an original typewritten sheet which is prepared in the usual manner by means of a special duplicator ribbon.

This original sheet is placed in the carriage and the carriage is moved over the printing bed thereby applying the original sheet face downward on the gelatin surface of the printing bed. This original sheet is then removed from the printing bed and blank sheets are inserted in the carriage one at a time and impressed on the gelatin surface thereby transferring the typewritten matter from the gelatin surface to the copy sheet. This usual

method provides only a limited number of copies from each original sheet and my invention is therefore intended to provide a means and method whereby a substantially increased number of copies may be made from a single original typewritten sheet.

In my invention I provide an original typewritten sheet in the usual manner so far as the face side of the sheet is concerned. In the preparation of this original, however, special duplicator carbon paper is used whereby a carbon copy in reverse is printed on the back of the original. This original sheet is then used in the duplicator in the usual manner, i. e., by transferring the typewritten matter to the gelatin surface of the printing bed by applying the original thereto face down, then removing the original and making the usual limited number of copies from the gelatin surface. This same original typewritten sheet is then placed in the carriage face down and applied to the gelatinized surface thereby leaving the reversed carbon copy exposed on the back of the original. This original sheet is then left on the gelatin to form a printing surface and copy sheets are inserted in the machine and the bottom surface of each copy sheet is automatically moistened as it is applied to the back of the original as the carriage is moved over the printing bed. Each copy sheet thereby receives an impression from the carbon side of the original and a further limited number of copies may be made in that manner.

It is therefore obvious that by means of my invention both sides of the original copy may be prepared during a single typewriting operation and that a considerably increased number of duplicate copies may be obtained therefrom.

It should be noted that the first set of copies is obtained from the impression which is transferred to the gelatin sheet from the face of the original. The second set of copies is obtained from the carbon impression on the back of the original which latter is used as a printing surface.

One of the important features of my invention is the provision of means whereby the face of the copy sheets may be automatically

moistened during the operation of applying them to the printing surface. I also provide an adjustable means for accurately adjusting the moistener to a position whereby the 5 desired amount of moisture may be applied to the sheets.

A further object is to provide an efficient means whereby the moistener may be accurately adjusted in such a manner that the 10 copy sheets may be inserted in the carriage in the usual manner and that the platen roller in its normal movements will bring the copy sheet effectively into contact with the moistener as the sheet is being applied to the 15 printing surface.

Another object is to provide an adjustable moistener preferably resiliently mounted whereby a yielding pressure may be applied either to the surface of the copy sheets or 20 to the surface of the printing bed as desired or whereby the moistener may be so adjusted as to allow the duplicator to be used in the usual manner without the application of moisture.

25 Further objects will be apparent from the specification and the appended claims.

In the drawing:

Figure 1 is a transverse sectional view through a carriage and a portion of the 30 printing bed of a duplicator somewhat similar to that shown in the co-pending application, Serial No. 529,629, previously mentioned, and illustrates one embodiment of my invention in cooperative relation with the 35 platen roller; and

Fig. 2 is a fragmentary perspective view of one end of the moistening reservoir and moisture applying means supported thereon. The opposite end of the reservoir and the 40 adjusting mechanism for the moisture applying means is exactly similar to that shown and it is believed that the construction will be understood without further illustration.

Referring to the drawing in detail, the embodiment illustrated comprises a printing bed 1, having the usual printing surface thereon which surface is provided by means of the usual gelatinized apron 2. A carriage 3 comprises the usual rectangular frame work 45 and is provided with a platen roller 4 rotatably mounted on arms 5 which latter are secured to a rock shaft 6 pivotally mounted in the carriage frame. The rock shaft is provided with a handle 7 by which the carriage 50 may be moved back and forth over the printing bed. The platen roller and the associated handle are mounted in a manner to provide a lost motion movement of the handle and roller relative to the carriage whereby the 55 handle and roller may be moved to the position indicated by dotted lines in Fig. 1, the platen roller thereby being raised and lowered during each cycle of operation.

A pressure roller 8 is mounted in the carriage frame in a position to cooperate with

the platen roller in directing sheets of paper onto the printing surface. This pressure roller 8 is usually resiliently mounted in a manner similar to that shown in the co-pending applications previously mentioned.

Any of the usual types of margin bars may be employed but in the present instance I have diagrammatically illustrated a rotatable margin bar 9 which cooperates with the platen roller for the control of the paper as it is being applied to the printing bed. The construction and operation of this margin bar is illustrated and described in the previously mentioned co-pending application, Serial No. 529,629.

An angularly positioned table 10 is mounted on the carriage in a position to direct the original or copy sheets 11 between the pressure roller and the platen roller when the platen roller is raised at which time the margin bar is in a position to receive and support the edge of the paper. The carriage is provided with an inwardly extending shelf 12 on which may be supported a reservoir 13 to receive a suitable moistening fluid, the reservoir being provided with a cover 14.

Threaded rods 15 are secured to the reservoir and extend through clearance holes in the rear wall of the carriage frame. Compression springs 16 are mounted on these rods 25 between the reservoir and the carriage wall and tend to move the reservoir toward the platen roller. The threaded rods 15 are provided with thumb nuts 17 whereby the position of the reservoir may be accurately adjusted in any desired relation to the platen roller. Lock nuts may be provided for these thumb nuts if desired. The moistening device comprises a wick 18 projecting through the outwardly extending portion 19 of the reservoir, the outer end of the wick being in contact with a moisture applying roller 20.

The roller 20 is resiliently mounted as shown in Fig. 2. A similar mounting means is provided at each end of the reservoir whereby the roller 20 is resiliently mounted and comprises levers 21 on which the roller is pivotally mounted, the levers also being pivotally mounted at 22 on the side of the reservoir. The outer end of these levers comprise comparatively thin flat springs 23 which are secured to the levers 21. The outer end of each spring is in contact with an adjusting screw 24 which is threaded in a bracket 25 on the end of the reservoir. The flat springs 23 are held in contact with the adjusting screw 27 by means of a relatively strong tension spring 26.

It will be obvious from an inspection of the drawing that the reservoir and the associated moistening means may be so adjusted that when the platen roller is raised the paper may be inserted between the platen roller and the pressure roller and supported in the usual manner on the margin bar and that when the

platens roller is lowered to the full line position shown in Fig. 1 the paper 11 will be moved to the position shown so that its lower surface will be in contact with the resiliently mounted moistening roller 20. This roller is adjustable by means of the screw 24 to provide the desired yielding pressure against the paper.

By means of the construction herein described the reservoir and moistening means may be moved out of operating position so that the duplicator may be used in the usual manner for obtaining the entire limited number of copies from the face of the typewriter 15 ten or otherwise prepared original.

When it is desired to moisten the surface of the paper in order to obtain copies from the back or reversed carbon side of the original typewriter sheet 11a which has been applied to the printing bed the moistener may be moved forward to contact with the sheets whereby each consecutive copy sheet will be moistened as it is applied to the printing surface of the sheet 11a. By this method a second supply of copies may be obtained from the carbon side of the original sheet.

It is sometimes desirable to moisten the gelatinized surface of the printing bed during the back and forth movement of the carriage in the normal operation of the machine. When this is desired the moisture roller adjusting screw 24 may be adjusted to allow the roller 20 to be moved downwardly into yielding contact with the gelatinized surface of the apron 2 as indicated by the dotted lines in Fig. 2, in which position it will be yieldably retained by means of the tension spring 26 and the flat spring 23 and during each back and forth movement of the carriage the gelatinized surface will be moistened to a desired degree depending upon the adjustment of the moistening roller.

It will, of course, be understood that a special moistening fluid which is adapted for use with the particular duplicating material used may be supplied in the tank 13 for the purpose of moistening the backs of the copy sheets or the printing surface.

The roller 20 may be made of any desired material suitable for applying moisture in accordance with the duplicating material used. Porcelain may be used for this purpose.

In order that the copy sheets may be held accurately in registered position as they are being applied to the reverse side of the original sheet 11a, which latter has previously been applied to the surface of the printing bed, the carriage stops may be moved slightly so that a small portion of the margin of the copy sheet 11 will be applied to and stick to the gelatinized surface adjacent the edge of the sheet 11a, as shown at 27. This overhanging edge of the copy sheet on the gelatine retains the paper accurately in alignment during the printing process.

When it is desired to make a larger number of copies of original typewritten or otherwise prepared copy than can be produced from the face and back of the original sheet, further originals may be prepared by placing another carbon sheet back to back with the original carbon sheet during the preparation of the original copy. A second sheet is placed against the second carbon paper and the copy is prepared in the same manner as originally described thereby producing an original copy having the typewritten matter in reverse on the back thereof and a second carbon copy which may at any time be applied to the gelatin printing surface, thereby leaving an impression from which still more copies may be made.

By this method at least three times the number of copies may be obtained than with the usual method of using a single original.

While I have illustrated by one embodiment of my invention, it will be understood that various modifications may be made without departing from the spirit of the invention and I therefore desire to be limited only by the prior art and the scope of the appended claims.

Having thus described my invention, what I claim and desire to secure by Letters Patent is:

1. The method of duplicating comprising preparing an original sheet having transferable copy on the face thereof and similar transferable copy in reverse on the back thereof, applying the face of said original to a hectograph printing surface to transfer the original to the printing surface, then applying consecutively blank sheets to the hectograph to provide a limited number of copies, then applying the original to the hectograph surface and thereafter applying blank sheets to the reverse side of the original to provide a further limited number of copies.

2. The method of duplicating comprising preparing an original sheet having an original copy on the face thereof and reversed copy on the back, applying the face of the original to a hectograph printing surface to transfer the original to the printing surface, then applying a limited number of blank sheets to the printing surface to obtain copies therefrom, then applying the original sheet face down on the printing surface, then applying blank sheets to the back of the original to obtain a further limited number of copies and applying moisture to the contacting surface of the copy sheets during the process of applying the sheets to the back of the original.

3. A duplicating machine including a printing bed and a carriage movable thereover, means on said carriage for transferring sheets to said printing bed, and automatic means for moistening said sheets as

they are being applied to said printing bed.

4. In a hectograph machine having a printing bed and a carriage movable over said bed, a platen roller on said carriage for applying copy sheets to said bed, and a moistener device arranged to apply moisture to said sheets as they are transferred to said bed.

5. In a hectograph machine having a printing bed and a carriage movable back and forth over said bed, a movable platen roller on said carriage for transferring sheets to said bed, a moistener on said carriage, said platen roller being arranged to automatically bring said sheets in contact with said moistener while they are being applied to said bed.

6. In a hectograph machine having a printing bed and a carriage movable over said bed, a movable platen roller on said carriage and arranged to apply sheets to said bed during the movement of said carriage, and a moisture transferring device on said carriage and arranged to yieldingly contact 25 with said sheets during their application to said bed.

7. A hectograph machine having a printing bed, a carriage movable over said bed, a platen roller on said carriage and movable 30 to and from said bed, means for supporting sheets on said carriage when said platen roller is in raised position, a moistener on said carriage, said platen roller being arranged to move said sheets into contact with 35 said moistener when said platen roller is in its lowered position.

8. A hectograph machine having a printing bed, a carriage movable thereover, a platen roller in said carriage and movable 40 to and from said bed, means for supporting sheets in said carriage when said platen roller is in raised position, said platen roller being arranged to apply said sheets to said bed when said carriage is moved thereover, and 45 automatic means for applying moisture to said sheets during the movement of said carriage.

9. A hectograph machine including a printing bed, a carriage movable thereover, 50 a pressure roller on said carriage, a platen roller on said carriage and movable to and from said bed, said pressure roller and said platen roller being arranged to receive a sheet therebetween when the platen roller is in 55 raised position, a moistener on said carriage, said platen roller and said pressure roller being arranged to engage said sheets therebetween when said platen roller is in lowered position and to simultaneously cause the 60 engagement of said sheet and said moistener.

10. A duplicator including a printing bed having a carriage movable thereover, means on said carriage for applying sheets to said bed, a moistener on said carriage arranged to 65 moisten said sheets as they are being applied

to said bed, said moistener comprising a reservoir, a moisture applying roller cooperating with said reservoir and means for adjusting the position of said roller to apply a predetermined pressure to said sheets. 70

11. A hectograph machine including a printing bed, a carriage movable over said printing bed, means on said carriage to apply sheets to said bed during movement of said carriage, and automatic means to apply moisture to said sheets as they are being applied to said bed, said moisture applying means being adjustable to apply moisture to said bed instead of to said sheets. 75

12. A duplicator including a printing bed, a carriage movable over said bed, means on said carriage for applying sheets to said bed, a moistener on said carriage, and adjustable means to cause said moistener to apply moisture to said sheets or to said bed during the 80 movement of said carriage.

13. In a hectograph machine including a printing bed and a carriage movable thereover, a platen roller in said carriage for applying sheets to said bed, a moisture applying means on said carriage, and means for moving said moisture applying means to or from said bed and arranged to apply a yielding pressure against either said bed or said 85 platen roller. 90

14. In a duplicator having a printing bed and a carriage movable over said bed, means on said carriage for consecutively applying sheets to said bed, a moistener on said carriage for applying moisture to said sheets as they are being applied to said bed, said moistener comprising a reservoir having a moisture applying means associating therewith, and adjustable means associated with said moisture applying means to cause said 95 moisture applying means to exert a yielding pressure against either said bed or said sheets. 100

15. A hectograph machine including a printing bed having a carriage movable thereover, means on said carriage for applying consecutive sheets to said bed, a moistener on said carriage for applying moisture to said bed as the carriage is moved thereover, said moistener comprising a reservoir adjustable toward and from said sheet applying means, means associated with said reservoir for applying the moisture, and means for adjusting said moisture applying means toward or from 110 said bed. 115

In witness whereof, I have hereunto subscribed my name.

LOUIS J. SAUER.
